R. D. SMITH

DETENT TRIPPING MECHANISM FOR SOCKET SWITCHES

Filed Nov. 8, 1920

UNITED STATES PATENT OFFICE.

RAYMOND D. SMITH, OF SCARSDALE, NEW YORK, ASSIGNOR, BY MESNE ASSIGNMENTS, TO TREMONT PRODUCTS CORPORATION, OF BOSTON, MASSACHUSETTS, A CORPORATION OF MASSACHUSETTS.

DETENT-TRIPPING MECHANISM FOR SOCKET SWITCHES.

Application filed November 8, 1920. Serial No. 422,751.

This invention relates to a detent-tripping arrangement, specifically but not exclusively for pull socket switches, wherein a common, manually actuatable means is employed co-operatively with a resilient means and a detent to tension a controlled mechanical element for movement normally prevented by said detent and subsequently to release said element from restraint by said 10 detent by mechanically tripping the latter.

The broad object of the invention is to provide in a partially automatic apparatus (such as a pull socket switch partially governable by a thermostatic detent) having a 15 single, manually actuatable element for controlling the same (such as a spring restored pull chain), a tripping mechanism whereby when tension is established by one full stroke of said element for later causing 20 automatic detent-delayed movement of an operative part (such as a switch circuit controller) a subsequent manual actuation of said element will operate to trip the detent and release said part immediately to 25 permit its said movement.

The novel principles embodied in my present invention may advantageously be applied to delayed cut-offs for pull sockets of the general type disclosed in my co-pending application, Serial No. 421,556 filed Nov. 3, 1920. The type of switch here employed as the delayed cut-off above mentioned includes a current distributor arranged to be established under tension tending 30 to move the same to break the circuit but permitted so to move only upon thermostatically caused retraction of a normally restraining detent, such retraction taking place after a substantial interval of time 35 such as that required for the thermal energization of the thermostat by the electric current. In the most simple form of the above described switch, however, no means is provided for manually causing direct and 40 immediate circuit-breaking switch action if desired but the operator must always wait upon the delayed-acting automatic switch action above described.

The only means that have heretofore been 45 provided in this connection for manually causing direct and immediate cut-off action independently of the thermostatic delayed acting detent has consisted in a co-operative

formation of the engaging portions of the above mentioned current distributor and 55 the thermostatically controlled detent hook, whereby an unusually forceful pull on the switch control chain operates to force the detent hook out of engagement with the distributor by excessive thrust of the latter on the intercepting portion of the former to permit circuit-breaking movement 60 of the distributor. This arrangement depends in operation upon a proper balancing of co-operative spring forces and causes 65 strain and wear upon parts necessarily employed which are comparatively small and delicate.

Accordingly, in applying my invention to improve the operating conditions described above, the particular object is to provide a tripping device for the detent hook whereby, preferably, a repetition of the initial stroke of the pull chain subsequent to the stroke thereof that places the 70 current distributor under tensioned restraint by said detent hook, is operative to retract the detent hook from intercepting engagement with the distributor in a natural, unstrained and mechanically proper manner. 80

Other objects and advantages of my invention will be pointed out in the following description of a preferred embodiment wherein the objects recited above are accomplished. This particular embodiment, 85 herein disclosed merely to illustrate the principles of the invention, constitutes a pull socket switch of conventional outward form as shown on the accompanying drawings in which:

Fig. 1 is a view of the complete socket switch in elevation, the casing and certain other parts being partially broken away to show the interior switch structure in which is embodied my improved detent tripping 90 mechanism.

Fig. 2 is a plan view of the switch mechanism taken partly in section on the plane 2-2 in Fig. 1 and showing the relation of parts when the lamp circuit is normally 100 closed.

Fig. 3 is an enlarged fragmentary view in elevation looking in the direction of arrow 3 in Fig. 2, but showing the switch rotor positioned for circuit breaking movement and restrained in circuit making posi- 105

tion by a thermostatically controlled detent. Fig. 4 is an enlarged fragmentary view looking in direction of arrow 4 in Fig. 2, and is explanatory of the paths of movement of certain parts.

Fig. 5 is also an enlarged fragmentary view in plan indicating the movement of the thermostatically controlled detent parts.

Fig. 6 is a view looking in direction of arrow 6 in Fig. 5.

Fig. 7 is a fragmentary illustration of the lost motion tooth engagement concerned in the detent tripping operation.

Fig. 8 illustrates a modification of the tripping mechanism.

Fig. 9 is a front elevation of the structure in Fig. 8 showing certain parts sectioned on plane 9—9 of that figure.

Fig. 10 shows a further modified form of tripping mechanism.

In the drawings, a single part when appearing in more than one view is designated by the same reference numeral.

In general construction the socket switch structure incorporating my improved detent tripping mechanism is of the usual form comprising within an outer casing 9 and retaining cap 10, two bracket-connected upper and lower blocks 11 and 12 respectively between which is mounted the switch mechanism, and from the lower of which blocks depends the threaded receptacle 13 for an incandescent lamp 14, two of the block-connecting brackets having binding post screws 16, 16 to accommodate the socket lead wires 17, 17.

The switch mechanism includes a centrally pivoted, axially slidable, conductive plate rotor 20, having oppositely disposed contact-wiping arms 21 suitably formed to ride over stationary, inclined contact plates 22 for controlling the lamp circuit. The rotor 20 is rotated in stages and at each full increment of rotor movement the arms 21, 21 are advanced progressively over one of two pairs of diametrically opposite inclined steps, one of said pairs comprising the blank steps 25, 25 and the other of said pairs comprising the steps 26, 26 which carry respectively the contact plates 22, 22, above mentioned.

The rotor 20 is advanced by successive forward strokes of an oscillatory actuator 30, axially slidable with the rotor on the common pivot post 29, through the one-way driving engagement of pawl teeth 31 on said actuator with corresponding ratchet teeth 32 on said rotor, such engagement being established by the coiled spring 33, which exerts axial tension pressing the actuator against the rotor and the rotor against the incline steps and which also exerts torsional tension on the actuator operative after a driving stroke thereof to return it to the beginning of its stroke, or positioned against

the stop 34 (as shown in Fig. 2). The bracket 35 limits the driving stroke of the actuator in the other direction, and insulating shoulders 36, terminating each of the incline steps 25 and 26, serve as stationary ratchet teeth to prevent return of the rotor plate 20 with the actuator 30 after a full driving stroke of the latter.

The relative position of the actuator stops 34 and 35 and of the step shoulders 36 is such that a full driving stroke of the actuator advances the plate arms 21 fully over the shoulders which terminate the steps 25, 25 after which the actuator will obviously be returned by spring 33 and in its lowest rotative plane to such an extent that the pawl teeth 31 retreat to a position for engagement with the next succeeding ratchet teeth 32 respectively and in my present improvement I so position the stop 34 that on each return of the actuator the extent of its retreat is sufficient to provide an appreciably lost motion or back-lash in the tooth-engaging relation such as shown at 37 in Fig. 7. The purpose of this back lash is, to permit each return of the actuator the extent of its retreat is sufficient to provide an appreciably lost motion or back-lash in the tooth-engaging relation such as shown at 37 in Fig. 7. The purpose of this back lash is, to permit in one position of the parts, a repetition of the initial part of the actuator driving stroke, before driving engagement occurs between the pawl and ratchet teeth 31, and 32,—this repeated movement being utilized for tripping a detent in a manner and for a purpose later to be described.

The position of the shoulders 36 that terminate steps 26, 26, however, is such that the arms 21, 21 have not passed said shoulders at the time the actuator 30, on a subsequent full driving stroke, is stopped by the abutment 35; and it should be noted that the angular formation of the terminal portions 38, 38 of contact plate 22, 22 is such that when the actuator is so stopped, the arms 21 have barely passed the summit of these terminal portions and are positioned as indicated at 21^a in broken lines in Fig. 3. In this position, however, the axial tension in spring 33 tends to cause said arms 21 to slide rotatively forward, and to be discharged from contact plates 22 onto the succeeding blank steps 25, 25, to break the circuit through the lamp. Before such discharge takes place, however, the rotative advance of the rotor 20 is positively arrested by engagement of a projecting spur 44 on the edge of the rotor 20 (of which there are two on diametrically opposite sides of the rotor) with a detent hook 40, pivoted to swing on a stud 41 mounted on the insulating block 12. At this time the plate rotor 20 and its arms are positioned as shown in full lines in Fig. 3.

The electric circuit connections and contact arrangement are such that advance of the rotor 20 to its position shown in Fig. 3 electrically energizes a normally de-energized resistance wire 45 that is wound about

and in heating relation to a bi-metallic thermostat 46 anchored at one end to the bracket 47, so that heat begins to be delivered to said thermostat and after a designed interval of time required to raise the thermostat to a certain temperature (which time may conveniently be from one to two minutes) a straightening, or outbending, of the thermostat occurs sufficient to retract the detent hook 40 from restraining engagement with spur 44 as shown in Fig. 5. The spring 33 then acts to discharge the rotor as above described automatically to extinguish the lamp. When so discharged, the rotor spur 44 drops to a lower plane than the intercepting end of hook 40, so that said hook does not become again operative to prevent further advance of the same spur when the thermostat cools.

It may be desired, however, to cause circuit-breaking movement of the switch rotor 20 independently of this thermostatically-caused detent release which depends for operation on action of the electric current. Especially is this true of the types of pull socket switches disclosed in my co-pending applications, Serial No. 422,750, filed Nov. 8, 1920, and Serial No. 421,554 filed Nov. 3, 1920, to which types of switches my present improvement is equally adaptable. Among other accomplishments the present invention specifically provides an improved means to this end, in a form of mechanism whereby the detent hook 40 may be mechanically and directly tripped by a partial forward stroke 35 on the actuator after its return from the forward or driving stroke that places the rotor under control of the thermostatically operated detent hook 40.

In the present embodiment of my invention a tripping extension for said detent hook is provided, preferably in the form of a light leaf spring 50, that may be riveted or otherwise secured to the hook 40 and extending therefrom inwardly in substantially a tangential relation to the circular path of a peripheral edge of the actuator 30. This actuator, as commonly constructed, comprises a relatively thick segmentary plate 51 made of fibre, or other suitable insulating material, secured to the under surface of which is a relatively thin, punched-metal piece 52 formed to serve as a hub for the actuator, and from which piece the pawl teeth 31 are struck downwardly. The plate 51 also carries spaced radially outwardly from the hub piece 52, a punched-metal channel-guide anchorage 53 for the pull chain 55. The peripheral edge of the actuator above referred to may comprise merely the edge of the relatively thick fibre plate, which as herein shown, is formed with a radially outwardly extending spur formation 56.

It will be clear that the normal travel of the spur formation 56, during a normal driving stroke of the actuator, is normally in a

helical path relative to the axis of oscillation of the actuator, because of the mounting of the incline steps 25 and 26 by the rotor arms 21. This helical path is indicated by the successive spur positions shown by broken lines in Fig. 4. It will be apparent from the drawings that the tripping extension 50 does not extend into said normal helical path of the spur, but that said extension lies in a higher plane than the spur 56 normally occupies at the time it rotatively passes said extension. Although the tripping extension 50 is axially removed from the said helical path it is clearly shown in Figs. 2 and 5 that the end of said extension 80 is normally positioned within the circular radial extent of said path, so that engagement of said extension with said spur will occur if the actuator 20 is maintained substantially in its highest plane when it is returned to the beginning of its driving stroke. When the rotor 20 is arrested in its position as shown in Fig. 3, however, it is evident that the actuator will be maintained in its highest plane, as shown in that figure, so that on return of the actuator after the driving stroke that so positions said rotor, the spring leaf tripping extension 50 will yield radially outwardly to permit the passage of the spur 56 near the end of the return actuator stroke, immediately snapping back into the path of said spur after the passage of the latter, so that at the beginning of a subsequent forward stroke of the actuator, the spur is operative to trip the detent 40 through longitudinal thrust on the extension 50, and before driving engagement occurs between teeth 31 and 32, because of the backlash shown in Fig. 7 and heretofore described.

This tripping of the detent releases the rotor for its spring caused discharge from the contact plates 22 exactly as in the case of thermostatic retraction of the detent; and the rotor spur 44 and the actuator spur 56 both drop instantly to their lowest plane, as indicated by the positions 44^A, and 56^A, respectively, in Fig. 4, whereby the rotative parts are free for further advance circuit-controlling movement.

In Fig. 5 the broken line position of the resilient detent extension 50 shows the change in position of this extension relative to the path of the actuator spur 56 when the thermostat is heated. It will be understood from reference to this figure and to Fig. 4, that such change in position of the extension 50 constitutes in general a movement radially inwardly toward the actuator pivot 29 and an advance movement along the circular path of the actuator spur, so that the latter may be at a higher point at the time of passing the extension and may thereby be in danger of interference with said extension as said spur rotatively advances and simultaneously

rises to a higher plane. Such interference would be of a nature to cramp and distort the resilient extension 50, as the actuator spur would be beneath and operative to force the extension upwardly edgewise. To prevent such condition the extension 50 is formed with a cam ear 57 at the bottom edge of its free end, and a co-operative bevel is formed at 58 on the upper peripheral edge of the actuator fibre plate 51, in the vicinity of the spur 56,—this cam ear and bevel co-acting to cause a natural and unstrained yielding of the extension 50 in its designed direction of flexure away from the path of the actuator, to prevent possible injury to the extension 50, if the switch is actuated before the thermostat has become cool. The nature of the impingement that under these conditions might occur between the bevelled edge of 58 of the actuator and the cam ear 57 is clearly shown in Fig. 6.

It will be appreciated that the arrangement described above utilizes a natural condition of relative and absolute actuator movement already inherent in the well known type of pull socket switch for producing a permutation detent tripping function that provides for the operator the ability by successive manual strokes on the actuator pull chain to conveniently and selectively establish the switch in any of its designed operating positions, without delay or constraint, and requiring no special or unusual method of chain-manipulation.

Specifically, the operative effects that are available by the operator in a socket switch embodying my improved detent tripping mechanism are the ability by successive actuations of the usual pull chain first, to light the lamp by one full stroke of said chain; second, when through with the light to actuate the switch by a subsequent pull chain stroke for automatically effecting delayed lamp extinguishment; third, to cause immediate and undelayed extinguishment of the lamp, if desired, by repeating the initial part of the last mentioned stroke; or as an alternative to this last mentioned operation, a repetition of the full chain stroke that actuates the switch to effect delayed automatic lamp extinguishment, may be made, which will momentarily extinguish the lamp, but immediately reestablish it in normally lighted condition, for continuous use.

I have thus provided a pull socket switch free from undesirable mechanical features, either as to complication or delicacy, and a switch that is manually governable by a single pull chain to light and extinguish a lamp as usual, but also containing means, operative when desired, to delay the circuit breaking action of the switch.

It is to be understood that the mechanical principles underlying my invention do not limit its embodiment to the exact or even

substantial form heretofore described. For instance, as shown in Fig. 8, I may mount a resilient tripping extension on the actuator fibre plate 51 and arrange the same for yielding flexure, not in a radial plane relative to the axis of the actuator pivot, but in a plane substantially parallel to said axis. In this case, I may employ a rigid projection 61 extending from the detent hook 40 to a position for being tripped by said extension 60 according to the operative principles of my invention heretofore described.

In Fig. 10, a modification is shown wherein provision is made for varying the nature of displacement of the tripping extension 80 when the thermostat moves to its heated position as shown in Fig. 5. Here the tripping extension appears as a rigid strut arm 62 pivoted at 63 and having a stop limiting spur 64. The strut arm 62 is yieldingly 85 maintained in its normal full line position by a light leaf spring 65 that may conveniently be anchored in a slot in the top of hook pivot stud 41 so that the strut may move back as required to some such position as is 90 shown in dotted lines in Fig. 10 when engaged by the actuator in its return movement. A projecting bracket 66 also extends from this stud and has a turned down extremity 67 engaging with the tripping arm 95 62 to limit the movement of the same toward the center of the switch structure,—the operative effect of said constraint being to prevent interference-causing displacement of the tripping extension 62, such as shown in 100 Fig. 5. Obviously a constraining bracket such as 66 could be employed with the type of tripping extension shown in Figs. 1 to 6 inclusive, in place of said cam ear and bevel formations.

The features of the improvement residing in the thermostatic control mechanism 40, 41, 46 etc. and co-operative switch contacts 21, 22, 38 etc. per se, are not claimed in this application but are the subject matter of 110 claims in my co-pending application Serial No. 421,556, filed November 3, 1920.

The pull socket structure herein disclosed is of the simple type for supporting and governing a single incandescent lamp, the 115 cooperative switch circuits terminating in rotor-bridged contact plates carried on two of only four detent step formations. The switch may however have more steps and more contact plates for governing additional circuits such as for a second switch-governed lamp or dimming device for the usual lamp. There would clearly be no definite sequence of operation to which such multiple switch arrangement would be restricted, such sequence depending entirely on the consecutive arrangement of steps and the thermo-detent tripping device herein disclosed could be applied equally well to any step.

Numerous other possible variations in 120

form and arrangement of details will suggest themselves to a mechanic and obviously the novel mechanical principles involved in my present invention are adaptable to 6 types of apparatus other than socket switches.

I do not, therefore, limit the scope of my invention to the exact purposes or embodiment herein described but what I claim as 10 new is:

1. In a switch, a detent controlling arrangement embodying in combination; a movable switch circuit controller; a manually operable oscillatory driving element for 15 said controller; resilient means energizable by a forward stroke of said element to tension said device for forward automatic circuit-governing movement; a detent normally arranged to prevent said movement; and 20 tripping mechanism for releasing said controller from restraint by said detent, operatively actuatable directly by a repetition of said forward stroke of said element.

2. An electric switch having in combination, relatively movable contacts; an oscillatory actuator with a limited stroke, including a spring automatically to restore it to a normal position, and arranged by full strokes alternately to close the switch and 30 to place it under control of automatic electric devices adapted to cause its delayed opening; said devices, including a detent normally adapted to prevent opening of the switch; and means co-operative between said 35 actuator and detent, when said switch is placed under control of said devices and when said actuator is then returned to its normal position, adapted to release said detent by further movement of said actuator.

3. Permutation switch mechanism embodying in combination, an oscillatory driving element having a limited stroke; and a driven switch circuit controller, both adjacently rotatable and axially slidable upon 45 a common pivot, said element and controller being maintained in pawl-and-ratchet driving engagement by tension exerted axially on said element; a contact-carrying step disposed in the path of said controller to oppose said tension and formed to present a 50 riding surface thereto inclined obliquely to the plane of controller rotation, whereby mounting of said step by said controller causes said element to rise from a lower 55 plane at the beginning of its driving stroke to a higher plane at the end of said stroke; detent means operative to retain said controller near the top of said step, whereby said element is then retained in said higher 60 plane, during its return stroke; and tripping mechanism for said detent means positioned to be operatively engaged by said element only when the latter is near the beginning of its driving stroke and in said 65 higher plane, whereby a subsequent forward

stroke of said element actuates said mechanism to release said controller from restraint by said detent means.

4. In a pull socket switch for an incandescent lamp, the combination with a movable 70 switch circuit-controller progressively movable to light and extinguish the lamp by successive strokes of a manually-operable spring-returned actuator, of detent means operatively related to said controller and 75 electrically governed thereby automatically to delay the lamp-extinguishing movement of said rotor a substantial period of time after the stroke of said actuator adapted to cause said action; and means whereby the 80 repetition of said actuator stroke renders inoperative said detent means, thereby to cause immediate lamp extinguishment.

5. A pull socket switch having a step-by-step, rotatable, double-ended, conductive, 85 current-switching member; circularly disposed stationary contacts arranged to be engaged by the ends of said member, inclined along the axis of rotation of said member toward said member, and mounted on insulating formations constituting teeth to prevent movement of said member in one direction, the terminal portion of said contacts being oppositely inclined; an oscillatory actuator arranged, relatively to said member, 90 oppositely to said contacts, concentrically pivoted with said member, having pawl-and-ratchet engagement therewith, and further having a stop-limited stroke; a coiled spring arranged co-axially of the common pivot of 95 said member and actuator and to exert axial pressure and torsional stress on said actuator; electrical means, including a detent, arranged to hold said member in electrical contact on said terminal portion and then 100 to release said member; and tripping means for said detent arranged to be energized by said actuator only when the latter is returned rotatively to its normal position and is axially displaced by retention of said 105 member by said detent.

6. In a pull socket switch, embodying a circuit-controlling rotor; pawl-and-ratchet actuating mechanism therefor including a pawl device having a limited forward stroke 115 for rotatively advancing said rotor over angular contact carrying formations circularly arranged in the path of said rotor to prevent backward movement of the latter, and further embodying common resilient means 120 for rotatively returning said device to the beginning of its stroke and for maintaining operative engagement of said device with said rotor and thereby of said rotor with said formations, in combination; a stationary contact formation co-operatively arranged with an engaging portion of said rotor, in one position thereof, so that the thrust of said resilient means opposes backward movement of said rotor, and tends to 125 130

- discharge said rotor rotatively forwardly from said formation to break the circuit; a 5 detent normally positioned to arrest forward movement of said rotor from its said position; and tripping means arranged to be operatively actuated by said device only upon a repeated forward stroke of said device subsequent to the establishment of said rotor in its said position.
- 10 7. In a pull socket switch embodying a circuit-controlling rotor; pawl-and-ratchet actuating mechanism therefor including a pawl device having a limited stroke for rotatively advancing said rotor over angular 15 contact-carrying tooth-formations circularly arranged in the path of said rotor to prevent backward movement of the latter; and resilient means for rotatively returning said device after its stroke and for maintaining 20 operative engagement of said device with said rotor and of said rotor with said formations, in combination; a co-operative detent arrangement operative to arrest both advance and backward movement of said rotor 25 when the latter is established in a certain circuit making position by one advance stroke of said device; resilient means energized by said stroke of said device and tending to advance said rotor from its said position to break the circuit; and mechanism 30 for tripping said detent arrangement to release said rotor, operable by said device only upon a repeated forward stroke of said device subsequent to the establishment of said 35 rotor in its said position.
8. In an electric switch, including manually actuatable mechanism for tripping a switch governing detent that is normally movable between an interceptive and a retractive position by automatically-acting 40 means electrically governed through said switch, the combination, with said detent, of a pivoted oscillatory switch actuator normally constrained for limited advance and return strokes in a normal helical path relative to its pivotal axis; means to constrain the rotative oscillations of said actuator to substantially a single plane when said switch 45 is under control of said detent and automatically-acting means; a resilient tripping extension carried by said detent in said plane and arranged (when said detent occupies its said interceptive position) to lie within the radial extent of said helical path but axially removed from said path; and further arranged when said detent occupies its said retracted position to lie in said helical path; said extension being co-operatively positioned and formed with an engaging portion of said actuator to permit the rotative return stroke of said actuator in said plane, and to be engaged positively thereby to trip said detent upon the subsequent advance stroke of said actuator, together with a co-operative cam formation 55 on said detent extension and on said actuator arranged to cause normal yielding displacement of said resilient extension from the helical path of said actuator to permit the passage of the latter when said detent 60 occupies its said retracted position.
9. In an electric switch, including manually actuatable mechanism for tripping a switch governing detent, the combination, with said detent, of a pivoted oscillatory 65 switch actuator normally constrained for limited advance and return strokes in a normal helical path relative to its pivotal axis; means to constrain the rotative oscillations of said actuator to substantially a single plane when said switch is under control of said detent, a resilient tripping extension carried by said detent in said plane and arranged to lie within the radial extent of said helical path but axially removed from said 70 path; said extension being co-operatively positioned and formed with an engaging portion of said actuator to permit the rotative return stroke of said actuator in said plane, and to be engaged positively thereby to trip said detent upon the subsequent advance stroke of said actuator.
10. A detent and detent-tripping arrangement, embodying an oscillatory drive member having a limited stroke; a driven element; means including an element-engaging detent to detain said element after a full driving stroke of said member and further then to tension said element for automatic further movement and comprising instrumentalities adapted to cause such movement, said element, member, and means being co-operatively arranged so that said member, during its return stroke, is maintained in a different plane of rotation than that occupied by it after such further movement of said element; and a cooperative tooth formation on said member and resilient finger on said detent arranged to engage when said member is in said different plane, and then to permit escape of said member on its said return stroke, but then to release said detent from said element on a forward movement of said member.
11. A detent and detent-tripping arrangement, embodying an oscillatory drive member having a limited stroke; a driven element; means including an element-engaging detent to detain said element after a full driving stroke of said member and further then to tension said element for automatic further movement and comprising instrumentalities adapted to cause such movement, said element, member, and means being co-operatively arranged so that said member, during its return stroke, is maintained in a different plane of rotation than that occupied by it after such further movement of said element; and a cooperative tooth formation on said member and resilient finger on 115
- 120
- 125

- said detent arranged to engage when said member is in said different plane, and then to permit escape of said member on its said return stroke, but then to release said detent from said element on a forward movement of said member; said member and extension carried by said finger being also co-operatively formed and positioned to cause escapement of said finger from said member 10 on a forward stroke of the latter in the plane occupied by it after said further movement of said element.
12. In a pull socket switch adapted to be operated by successive actuations of a controlling pull chain, and incorporating agencies automatically operative to delay circuit breaking movement of the switch, means whereby successive actuations of said pull chain respectively make the circuit, establish the switch under control of said agencies and then move the switch directly to break the circuit.
13. In a pull chain operated socket switch, the combination of automatic mechanism arranged to cause self-delayed circuit-breaking movement of the switch, instrumentalities whereby one actuation of the pull chain energizes said mechanism, and means whereby a subsequent actuation of the pull chain 20 operates the switch directly to break the circuit.
14. A switch for an electric circuit having contacts, a contact controlling member movable by successive movements to make and break the circuit, slow action controlling instrumentalities to delay the circuit changing effect of the movement of said member for a substantial interval of time, and means whereby subsequent movement of said member establishes the circuit change irrespective of the action of said instrumentalities.
15. A switch for an electric circuit having contacts, a contact controlling member means to move the same for effecting a circuit change, slow action controlling means to delay the circuit changing effect of said member for a substantial interval of time after movement thereof, and means operative through subsequent movement of said member unretardedly to produce said circuit change.
16. A switch for an electric circuit having contacts, a contact controlling member movable by successive movements to make and break the circuit, slow action controlling instrumentalities to delay the breaking of said circuit for a substantial interval of time, and means whereby subsequent movement of said member may break said circuit immediately irrespective of the control by said instrumentalities.
17. A switch for an electric circuit having contacts, a contact controlling member movable by successive movements to make and break the circuit, a thermo-electric control device to delay the current changing effect of a movement of said member for a substantial interval of time after said movement, and means whereby subsequent movement of said member establishes said current changing effect irrespective of the control of said instrumentalities.
18. A switch for an electric circuit having contacts, a contact controlling member movable by successive movements to make and break the circuit, a thermo-electrically controlled detent to delay the current changing effect of a movement of said member for a substantial interval of time after said movement, and means whereby subsequent movement of said member withdraws said detent.
19. A pull socket switch for an incandescent lamp having contacts, an actuator, successive actuations of which make and break the lamp circuit, a thermo-electrically controlled detent to delay the breaking of the circuit, and means whereby a subsequent movement of the actuator withdraws the detent permitting immediate breaking of the circuit.
20. A socket switch for an incandescent lamp having an oscillatory actuator, a rotary contact controller adapted to be advanced progressively step by step by successive movements of the actuator to make and break the lamp circuit, a thermo-electric control device to delay the breaking of the circuit for a substantial interval of time, and means whereby a subsequent movement of the actuator serves to break the circuit irrespective of the control device.
21. A socket switch for an incandescent lamp having an oscillatory actuator, a rotary contact controller adapted to be advanced progressively step by step by successive movements of the actuator to make and break the lamp circuit, a thermo-electrically controlled detent to delay the completion of the circuit breaking movement of the controller for a substantial interval of time following the circuit breaking movement of said actuator, and a detent release mechanism adapted to be actuated by a subsequent movement of the actuator to cause immediate breaking of the circuit when desired.
22. A switch for an electric circuit having a movable circuit control member adapted to make and break the circuit, means to impart movement thereto to produce a given circuit changing effect, a detent to arrest the movement of the same to retard the said circuit changing effect of said member, a thermo-electric control device to withdraw the detent, and a detent control device movable independently of both said control member and said thermo-electric control device to independently withdraw said detent.
23. A lamp socket switch having a movable circuit control member adapted to make

and break the lamp circuit, a detent to arrest movement of the same to retard the circuit breaking movement of said member, a thermo-electric control device for the detent, a supplemental detent control movable independently of both the control member and the thermo-electric control device to independently withdraw the detent, and a manually operable actuator for said supplemental detent control.

24. A switch for an electric circuit having a movable circuit control member adapted to make and break the circuit, a slow acting control device combined with means to retard the circuit changing movement of said member for a substantial interval of time, means movable independently of said member and device for independently actuating said means to cause unretarded circuit changing movement, and actuating means for said independently movable means.

25. A socket switch for an incandescent lamp having a movable circuit control member adapted to make and break the lamp circuit, a manually operable actuator

adapted to move said member for lighting and extinguishing the lamp, a detent operatively related to said member, electrically governed means to control the detent to delay the lamp extinguishment for a substantial period of time after the lamp extinguishing movement of the actuator, and means to move the detent by a repetition of the actuator movement to cause immediate lamp extinguishment.

26. A socket switch for an incandescent lamp having an actuator adapted to operate the switch, and incorporating agencies automatically operative to retard lamp extinguishment for a substantial period of time following a lamp extinguishing movement of the actuator, and having also means to produce an unretarded extinguishment of the lamp through a subsequent actuation of the actuating device.

Signed at Boston, in the county of Suffolk and Commonwealth of Massachusetts, this 5th day of November, 1920.

RAYMOND D. SMITH.
